DISPENSING CONTAINER

Alfred J. Chamberlain, Wauwatosa, Wis.

Application October 10, 1934, Serial No. 747,674

13 Claims. (Cl. 221—11)

This invention relates in general to dispensing containers and more particularly to a novel dispensing spout arrangement and closure therefor.

5 Among the objects of the invention, one object is to provide a dispensing container of this character wherein the spout and its closure are so constructed and organized as to provide for the drain-back or return into the container of any 10 of the liquid which may not be entirely discharged or poured therefrom and also to provide not only for the closure of the discharge spout when the contents are not being dispensed but also for the complete and effective protection of all areas 15 of the spout over which liquid flows. These features especially adapt the container for dispensing beverages, syrups or the like, or, in fact, any substances which are liable to be contaminated or impaired in any way upon exposure to air or to dust or foreign matter.

20 Another object of the invention is to provide a closure for a container of this character which may be conveniently so constituted as to be chemically inert with respect to the contents of the 25 container.

A further object is to provide a device of the character described and having the advantages 30 enumerated which is simple and durable in its construction, economical to produce, readily and easily applied and removed and yet when applied provides an effective and secure closure and also an hermetic seal.

Other objects and advantages reside in certain 35 novel features of the construction, arrangement and combination of parts which will be herein-after more fully described and particularly pointed out in the appended claims, reference being had to the accompanying drawings, forming a part of this specification, and in which:

40 Figure 1 is a perspective view showing a dispensing container embodying the present invention;

Figure 2 is a fragmentary view on an enlarged 45 scale showing one type of closure in diametrical vertical section, parts being shown in elevation for the sake of illustration;

Figure 3 is a fragmentary view similar to Figure 2 but showing a slight variation in the construction of the closure and spout;

50 Figure 4 is a fragmentary view partly in diametrical vertical section and partly in side elevation showing another embodiment of the invention; and

55 Figure 5 is a similar view showing a modifica-

tion of the form of the invention illustrated in Figure 4.

Referring to the drawings, and more particularly to Figures 1 and 2, the numeral 1 designates a container similar in its general construction to the container of my Patent No. 1,903,442, granted April 11, 1933. The head 2 of the container has an inclined portion 3 as in the patent referred to and in the inclined portion a discharge opening 4 is provided. A pouring spout 5 is associated with the discharge opening. Pouring spout 5 is generally of cylindrical form and has its lower end interseamed with the margin of the discharge opening as indicated at 6. The upper or outer end of the spout 5 is flanged as at 7 and is cut off or shaped to lie wholly within the confines of the container.

A closure is provided for the discharge opening and consists of a two-part plug P, the lower part or section 10 of which may be of wood or other suitable material. The section 10 of the plug P has a reduced portion 11 designed to project down through the discharge opening and also has an enlarged portion or shoulder 12 designed to fit against the seat 13 presented at the point where the spout is interseamed with the margin of the discharge opening. The shoulder 12 has a beveled outer peripheral portion or seat 14 and also has a recess 15 in its top. The upper part 17 of the plug P has a reduced portion 18 slidably interfitted with the recess 15 and has a beveled peripheral portion 19 cooperable with the beveled portion 14 to define an approximately V-shaped recess in the periphery of the plug and intermediate the ends thereof. In the recess so defined, a sealing and securing element in the form of a ring or band of elastic material, such as rubber, is disposed. The beveled surfaces 14 and 19 are designed to engage the rubber ring 16 and compress and deform the same into securing and sealing relation with the spout and with the plug. The parts 10 and 17 are drawn toward each other and into operative position by means of a wing nut 20 threaded on a screw 21 secured to the part 10, and extending through an opening in the part 17 and in a cupped washer 22.

The form of the invention shown in Figure 3 is identical with that just described except that the spout and the head of the container are provided with annular grooves or recesses 25 to receive the securing and sealing element 16.

In the form of the invention shown in Figure 4 the container 1 has a head 2 and pouring spout 5 as before, and the construction of the closure is generally the same differing principally in the

fact that it is made entirely of sheet metal and makes provision for sealing of the container.

As illustrated, the inner section or part 30 of the plug is drawn from sheet metal into cup-like form and has around its upper edge portion a double flange formation 31 to provide a shoulder to engage against the seat 13 and to provide a beveled seat or surface 32 for the sealing element or ring 16. The outer section or part 35 of the plug is also drawn from sheet metal into cup-like form and has a reduced portion 36 telescoping into the flange 32 and adjacent such reduced portion has a beveled surface 37 engageable with the gasket 16 whereby the sealing ring 16 will be compressed between said surfaces 32 and 37 and deformed into the annular recess 38 of the spout.

The follower is urged to operative position by means of a wing nut 39 threadedly engaged with a stud 40 which may have its head 41 welded to the plug 30.

This construction lends itself readily to the application of a sealing cap 42 which may be inter-crimped with the spout as at 43. This sealing cap may have the conventional tearing tab (not shown).

The form of the invention shown in Figure 5 is identical with that shown in Figure 4 with the exception that the inner part of the plug corresponding to the part 30 instead of being a sheet metal drawing or stamping is made of wood or other suitable material. In this figure the inner part is designated at 45 and as before has a shoulder 46 which engages against the seat 13 and provides a seat for the sealing element 16. A wing nut 39 is employed as before but the stud with which it coacts and designated at 40' is designed for use with wood. The outer part or section of the plug is identical with that shown in Figure 4 and hereinabove described and is designated by like numerals.

A closure of the character described may be readily and easily applied and removed. When applied and secured in closed position the distortion of the sealing ring resulting from the action thereon of the cooperating beveled surfaces of the two parts of the closure plug provides not only for an hermetic seal but also for a secure mechanical interconnection. The embodiments of the invention shown in Figures 4 and 5 lend themselves also to the ready application of sealing devices required by law or by custom in connection with the distribution of some commodities.

While the invention in its various forms may be used to advantage with dispensing types of containers of the character shown, it is also adapted for advantageous use with other different and distinct types of containers. For example, it is capable of effective use with a pail type of container, that is to say, a container or receptacle which has an open upper end or an opening of substantial size in some other portion thereof. In any event, the invention makes use of the characteristics generic to the several modifications, namely, a sealing ring interposed between two cooperating parts which are drawn together to compress the ring and cause it to perform two functions, one the securing of the closure in place, and the other the sealing effect between the closure and the container.

While I have shown and described several constructions in which the invention may be advantageously embodied, it is to be understood that the constructions shown have been selected merely for the purpose of illustration or example and

that various changes in the size, shape and arrangement of the parts may be made without departing from the spirit of the invention or the scope of the subjoined claims.

The invention claimed is:

1. A dispensing container having a discharge spout and a closure for said spout comprising a plug adapted to be positioned in the spout and made up of a plurality of parts, said parts having confronting beveled portions defining a substantially V-shaped recess in the periphery thereof, a sealing ring of rubber in said recess, and means for securing said parts together to cause the beveled surfaces thereof to distort the sealing ring into secure sealing and mechanical engagement with the closure plug and with the spout.

2. A dispensing container having a discharge spout and a closure for said spout comprising a plug adapted to be positioned in the spout and made up of a plurality of parts, said parts having confronting beveled portions defining a substantially V-shaped recess in the periphery thereof, a sealing ring of rubber in said recess, and means for securing said parts together to cause the beveled surfaces thereof to distort the sealing ring into secure sealing and mechanical engagement with the closure plug and with the spout, said spout having a recess therein in which a portion of the sealing ring is seated to afford a positive interlock.

3. A dispensing container having a discharge spout and a closure for said spout comprising a plug adapted to be positioned in the spout and made up of a plurality of parts, said parts having confronting beveled portions defining a substantially V-shaped recess in the periphery thereof, a sealing ring of rubber in said recess, and means for securing said parts together to cause the beveled surfaces thereof to distort the sealing ring into secure sealing and mechanical engagement with the closure plug and with the spout, the inner part of the closure plug being made up of material chemically inert with respect to the contents of the container.

4. A dispensing container having a discharge spout and a closure therefor consisting of a closure plug adapted to be fitted in the spout, a sealing ring extending around the periphery of the plug and acting when compressed to provide a seal and a mechanical interlock between the plug and the spout, and releasable means for compressing said sealing ring.

5. A dispensing container having a discharge spout, a closure for the spout comprising a closure plug made up of a plurality of parts, a sealing ring interposed between said parts and between the periphery of the plug and the spout, means on the plug for compressing the sealing ring and urging it into sealing engagement with the plug and spout when compressed, and means operable from the exterior for releasably securing the parts of the plug together and for effecting operative action of said means.

6. A closure for a container having an opening and comprising a multi-part closure member adapted to close said opening, a deformable sealing and securing ring disposed between said parts at the periphery thereof and adapted to be engaged and deformed thereby into secure sealing engagement with said opening, and releasable means for drawing said parts together and into engagement with said ring, both of said parts being operatively removable from said opening.

7. A dispensing container having a discharge spout provided with a seat at its inner end, a

closure for said spout consisting of inner and outer parts, the inner part having a shoulder engageable with said seat, a sealing ring encircling the periphery of said parts, adjacent portions of said parts having surfaces engageable with said sealing ring for deforming the same into sealing and securing engagement with the closure and the spout when the parts of the closure are secured together, and releasable means 10 for securing the parts of the closure together.

8. A dispensing container having a discharge spout provided with a seat at its inner end, a closure for said spout consisting of inner and outer parts, the inner part having a shoulder engageable with said seat, a sealing ring encircling the periphery of said parts, adjacent portions of said parts having surfaces engageable with said sealing ring for deforming the same into sealing and securing engagement with the closure and the spout when the parts of the closure are secured together, releasing means for securing the parts of the closure together and comprising a stud secured to the inner part, the outer part having an opening through which the 20 stud projects, and a wing nut threaded on the projecting portion of said stud.

9. A dispensing container having a discharge spout, there being a seat at the inner end of the discharge spout, and a closure for said spout comprising a closure plug consisting of an inner part having a shoulder resting on said seat, the outer end of said inner part having an opening, an outer part having a portion slidably interfitted with said opening, the inner and outer 30 parts of the plug being provided with confronting beveled surfaces in their periphery portions, a sealing ring encircling the parts of the plug and adapted to be engaged by the beveled surfaces thereof when the parts of the plug are drawn together, whereby the sealing ring is deformed into sealing and securing engagement with the plug and spout and means for drawing the parts of the plug together.

10. A dispensing container having a discharge spout and a closure therefor comprising a closure 40 plug made up of a pair of cup-like sheet metal

sections, a sealing ring encircling said sections, said sections having portions effective when the sections are drawn together to deform the sealing ring into sealing and securing engagement with the plug and spout, and means for drawing 5 the sections of the plug together.

11. A dispensing container having a discharge spout and a closure for said spout comprising a closure plug made up of inner and outer parts adapted to fit in the spout, a sealing ring encircling the parts of the plug, said plug parts having means for deforming the sealing ring into sealing engagement with the plug and spout when the parts of the plug are drawn together, means for drawing the parts of the plug together and 10 including an operating element located within the confines of the outer part of the plug, the outer part of the plug being adapted to have interconnected therewith a seal for preventing unauthorized tampering with said operating ele- 20 ment.

12. A dispensing container having a discharge spout provided with a seat at its inner end, a closure for said spout consisting of a closure plug adapted to be fitted in and removed from the 25 spout and having a portion presenting a shoulder to said seat, an elastic ring extending around the periphery of the plug and acting when compressed to provide a mechanical interlock between the plug and the spout and maintain the 30 shoulder in desired relation to its seat, and releasable means for compressing said elastic ring.

13. A dispensing container having a discharge spout provided with a seat at its inner end, a closure for said spout consisting of inner and outer parts, the inner part having a shoulder presented to said seat when the closure is in position in the spout, an elastic ring encircling the periphery of said parts, adjacent portions of said parts having surfaces engageable with the 40 elastic ring for causing the same to secure the closure in the spout with the shoulder presented to the seat when the parts of the closure are secured together, and releasable means for securing the parts of the closure together. 45

ALFRED J. CHAMBERLAIN.
